UNITED STATES PATENT OFFICE.

WILLIAM RODERICK BARCLAY, OF LEICESTER, ENGLAND, ASSIGNEE TO UNITED SHOE MACHINERY COMPANY, OF PATERSON, NEW JERSEY, A CORPORATION OF NEW JERSEY.

MACHINE FOR OPERATING UPON THE HEELS OF BOOTS AND SHOES.

1,205,142.

Specification of Letters Patent.

Patented Nov. 21, 1916.

Application filed September 5, 1914. Serial No. 860,392.

To all whom it may concern:

Be it known that I, WILLIAM R. BARCLAY, a subject of the King of England, residing at Leicester, Leicestershire, England, have 5 invented certain Improvements in Machines for Operating upon the Heels of Boots and Shoes, of which the following description, in connection with the accompanying drawings, is a specification, like reference characters on the drawings indicating like parts in the several figures.

This invention relates to machines for operating upon the heels of boots and shoes and is herein illustrated as embodied in a 15 machine for scouring the corners of the heel at the junction of the breast with the edge.

It sometimes happens that at the junction of the corners of the heel with the shank of the sole there are left, after the heel 20 breasting operation, more or less pronounced bunches or burs of untrimmed material; and hitherto this material has commonly been removed by a knife in the hand of the operator. It is very desirable, however, that the 25 finished corners shall be smooth since otherwise they detract greatly from the appearance of the shoe.

One object of the present invention is to 30 remove these burs in a satisfactory manner. To this end one feature of the invention 35 comprises a scouring tool, means for rotating said tool in one direction when one corner of the heel is being scoured and means for rotating it in the opposite direction when the other corner is being scoured, 40 the direction of rotation in each case being such that each corner is scoured from the outside toward the center of the shoe. In this way the liability to produce ragged and unsightly edges is avoided.

During the heel breasting operation it sometimes happens, particularly when high heels are being operated upon, that the edge of the breasting knife trembles so that the 45 corners of the heel are given more or less wavy contours; or it may happen that the breasting knife twists slightly so that the corners of the heel are not properly located with respect to the medial line of the sole. 50 In the one case it is desirable to straighten the corners, and in the other to bring them to a common plane properly located with respect to the shoe.

To this end, as well as in order to facili-

tate the proper removal of the burs referred 55 to above, another feature of the invention comprises a scouring tool, two work rests located symmetrically with respect to said tool and means for moving a selected work rest to present a corner of the heel to said 60 tool. By presenting first one corner of the heel and then the other to the tool by means of work rests located symmetrically with respect to said tools, the corners may be brought into the proper common plane at 65 the same time they are straightened.

These and other features of the invention including certain details of construction and combinations of parts will be described in connection with an illustrative machine and 70 pointed out in the appended claims.

Referring now to the accompanying drawings,—Figure 1 is a perspective view partly in section of a machine in which the present invention is embodied; Fig. 2 is a rear elevation of the parts shown in Fig. 1; Fig. 3 is a view of the cam for operating the belt shifters, Fig. 4 is a plan of a portion of the machine showing in dotted lines a shoe in positions to have the corners of the heel 80 scoured, and Fig. 5 is a perspective showing more particularly the mechanism for reversing the direction of rotation of the scouring tool.

The illustrative machine comprises a shaft 85 1 mounted in suitable bearings in the machine frame, on one end of which is fastened by any suitable means a tool herein shown as a conical scouring wheel 3, the base or larger end of which is situated at the front 90 of the machine as shown in Fig. 1. On the conical surface of this wheel is mounted the scouring material 5, and in operation the shoe is moved so as to bring the corner of the heel into contact with the wheel so as to 95 remove any bur or bunch of untrimmed material. The shaft 1 also carries two loose pulleys 7, 9 and a driving pulley 11, which latter is fixed to the shaft 1. The loose pulley 7 is connected to the main driving shaft 8 100 by a crossed belt 13 and the pulley 9 by an open belt 15, and means are provided for shifting one or other of the said belts on to the driving pulley 11 so that the shaft 1 may be driven in one or the other direction 105 as desired. These means comprise two belt shifters 17, 19 which are pivoted at 21, 23 one on either side of the frame of the ma-

chine. The belt shifters are provided at their lower ends with cam rollers 25, 27 which engage respectively cam grooves 29, 31 formed on a cam 33, see Fig. 3, which is fixed to a cam shaft 35 mounted in suitable bearings in the machine frame.

Mounted on the front of the cam shaft 35 is a pulley 37 and secured to this pulley is a strap 39 each end of which is attached 10 to a double treadle 40. When one of the treadles is depressed the cam shaft 35 will be partially rotated in one direction and one of the belt shifters 17, 19 will be moved by its cam groove so as to shift its belt on 15 to the driving pulley 11 and so drive the shaft 1 and scouring wheel 3 in one direction, while when the other treadle is depressed the other belt shifter will be moved by its cam groove so that its belt will be 20 shifted on to the driving pulley and the wheel 3 rotated in the other direction. It will be seen that as one belt shifter shifts its belt from its loose pulley to the driving pulley 11 the other belt shifter will shift 25 its belt from the driving pulley to its loose pulley should its belt be driving the shaft 1 at the time the other belt shifter is operated. When the treadles are in their inoperative position the two belts are situated 30 on their loose pulleys as shown in Fig. 1.

The machine is provided with two work supports 41, 43, one of which is used when one corner of the heel is to be scoured and the other when the other corner is to be 35 scoured, and means are also provided for moving upwardly each one of the work supports so as to bring the corner of the heel into engagement with the roll B. Means are also provided whereby the work rest 40 appropriate for the particular corner only is raised to bring that corner into engagement with the wheel 3 when the said wheel is rotating in a direction such that the said corner will be scoured in a direction from 45 the outside of the heel toward the center of the shoe. In order to carry this into effect there are mounted on the cam shaft 35 two arms 45, 47, the arms 45 being adapted when the cam shaft 35 is rotated in one 50 direction as just described, to engage and raise the work support 41; and the arm 47, when the cam shaft is rotated in the other direction, to engage and raise the work support 43.

55 Each work support comprises a plate having projecting therefrom a ledge 49 against which the corner of the heel opposite to the one being operated upon is adapted to bear during the scouring operation. Each work 60 support is provided with a downwardly projecting stem 51 which is adapted to fit into the bore 53 of a thimble 55 and is held adjustably in position therein by means of a set screw 59. The thimble is adapted to 65 slide in a bearing in the machine frame and

is held normally in its lowered position by means of a spring 61 situated inside the thimble, one end of which bears against the bottom of the thimble and the other end against a pin 63, which passes through the 70 bearing in which the thimble slides and also through a slot in the said thimble. The pin 63 also serves to limit the downward movement of the work support under the action of the said spring.

75 Between the work supports 41, 43 is situated a guard 65 in the form of a circular metal plate which extends across the base of the wheel and is provided to protect the shank of the shoe from the said wheel. The 80 guard 65 is provided with a downwardly extending portion 67 which is secured by a belt, as shown in Fig. 1, to the machine frame so as to hold the guard in position.

In order to scour the corners of the heel 85 of a boot or shoe the shoe is positioned upon one of the work supports, as for example 43, which is appropriate to the particular corner to be treated, with that corner uppermost and with the apex of the angle at 90 the junction of the heel breast and the shank against the edge of the circular guard plate 65, the sole of the shoe from the heel to the toe projecting across said guard (see Fig. 4). The treadle which is appropriate to the 95 work support 43 is then depressed, with the result that the cam shaft 35 is turned in a counter-clockwise direction viewing the machine from the front. This will move the cam 33 so that the cam groove 29 will, 100 through the cam roller 25 on the belt shifter 17, move this belt shifter and cause it to shift its belt 13 on to the pulley 11. The belt 13 is driven in a direction such that when viewing the machine from the front 105 the wheel 3 will be rotated in a clockwise direction. The scouring wheel is thus first started up and thereafter by the continued actuation of the treadle the arm 47 will engage and lift the work support 43 so that 110 the corner of the heel will be moved up into contact with the wheel 3. The operation having been completed on this corner, the machine is stopped and the shoe is placed on the work support 41 in a position corresponding to that just described, so as to bring the unscoured corner into position in 115 readiness to be scoured. When the shoe is in position on the rest 41 the treadle which is appropriate to this rest is depressed and the other corner scoured in the manner previously described.

120 It will be understood that by having the means for lifting the work support and the mechanism for reversing the direction of 125 rotation of the shaft 1 operatively connected together the corner to be operated upon will be brought into engagement with the scouring wheel when the wheel is rotating in a direction such that it will scour the said 130

corner from the outside of the heel toward the center of the shoe.

It will be noted from an inspection of Fig. 4 that the work rests 41, 43 are located 5 one on each side of the frusto-conical wheel 3 and are symmetrically arranged with respect to said wheel, the plates 49 being parallel respectively to diametrically opposite elements of the frusto-conical wheel. 10 With this construction and arrangement of parts the corners of the heels of all shoes which have been operated upon will lie in a plane which bears a fixed relation to the medial line of the sole.

15 Although the invention has been set forth in connection with a particular machine it should be understood that the invention is not limited in the scope of its application to the particular machine shown and described.

20 Having thus described my invention, I claim as new and desire to secure by Letters Patent of the United States:

1. A machine for operating upon the corner of a heel having, in combination, an operating tool, means for rotating said tool, a work rest movable to present the corner of a heel to said tool, and a single treadle operated member for throwing said rotating means into operation and for moving said 30 rest to work presenting position.

2. A machine for operating upon the corners of a heel having, in combination, a tool, mechanism for rotating said tool, a work rest movable to present a corner of a heel 35 to said tool, a manually operated member, and connections between said member, said rotating mechanism and said rest whereby movement of said member moves the work rest to present a corner to the tool and 40 throws the rotating mechanism into operation.

3. A machine for operating upon the corners of a heel having, in combination, a tool, mechanism for rotating said tool, two work 45 rests adapted to facilitate respectively presentation of the two corners of a heel to the tool, and a single treadle controlled member movement of which in one direction moves one work support into operative position and causes the rotation of the tool in one direction and movement of which in the other direction moves the other work support similarly and causes rotation of the tool in the opposite direction.

50 4. A machine for operating upon the cor-

ners of a heel having, in combination, an operating tool, means for rotating said tool in either direction at will, work rests located one on each side of said tool and movable selectively to present one corner or the other 60 of a heel to one side or the other of said tool, and means dependent upon the work rest selected for movement for controlling the direction of rotation of said tool.

5. A machine of the class described having, in combination, a tool for operating upon the corners of a heel, two work rests each movable to present one corner of the heel to the tool, means for rotating said tool, and means for selectively moving said work 70 rests.

6. A machine of the class described having, in combination, a tool for operating upon the corners of a heel, two work rests each movable to present one corner of the 75 heel to the tool, said work rests being located symmetrically with respect to said tool, means for rotating said tool, and means for moving either work rest as may be desired.

7. A machine of the class described having, in combination, a rotary tool of frusto-conical shape for operating upon the corner of a heel, a work rest having a plate arranged parallel to an element of said tool, said plate having a ledge which serves as 85 a gage for one corner of the heel, and means for moving said work rest to present the other corner of the heel to the tool.

8. In a machine for scouring the edges of a heel that extend from the tread face to the 90 sole the combination with a scouring device and mechanism for causing the device to be driven in one or the other direction of means for relatively positioning the shoe and device so as to bring the edges one at a 95 time into operative relationship to the device, the said means and mechanism being operatively connected together in such a manner that when the edge to be scoured is in operative position the device will be 100 driven in a direction such that the edge will be scoured from the outside of the heel toward the center thereof.

In testimony whereof I have signed my name to this specification in the presence of 105 two subscribing witnesses.

WILLIAM RODERICK BARCLAY.

Witnesses:

FREDERICK WILLIAM WORTH,
FRANCIS JOSEPH VANN.

It is hereby certified that in Letters Patent No. 1,205,142, granted November 21, 1916, upon the application of William Roderick Barclay, of Leicester, England, for an improvement in "Machines for Operating Upon the Heels of Boots and Shoes," an error appears in the printed specification requiring correction as follows: Page 2, line 83, for the word "belt" read *bolt*; and that the said Letters Patent should be read with this correction therein that the same may conform to the record of the case in the Patent Office.

Signed and sealed this 30th day of January, A. D., 1917.

[SEAL.]

F. W. H. CLAY,
Acting Commissioner of Patents.
